STRAIGHT AND SLANT BOTTOM RULER OR
GAUGE FOR TROUSERSJoseph Montes, Brooklyn, N. Y., and Salvatore
Lo Presti, Hollywood, Calif.

Application May 7, 1952, Serial No. 286,488

3 Claims. (Cl. 33—2)

1

The present invention relates to special rulers and the like for use with men's garments, and especially to a tailor's trouser ruler or gage which we choose to term a straight and slant bottom ruler or gage.

The main object of our invention is to provide means for fitting a pair of trousers upon a customer in a tailor shop or clothing store.

Another object is to have such means that are equally useful when cutting trousers to length on a cutting table.

A further object is to have such a slant ruler and the like that is not only adapted for use with trousers to be cut with the bottom at a normal slight slant, but is equally well adapted for cutting the bottoms of trousers with a greater and more pronounced slant than the usual or normal.

It is also an object of our invention to provide such a special slant ruler or gage that has two entirely different and distinct indications of the slant position and the normal position on the ruler so that no confusion can occur in use.

A practical object is, of course, to have such a slant bottom ruler or gage that is simple to make and as simple to use, and which, withal is reasonable in cost to encourage wide distribution on the market.

Other objects and advantages of our invention will appear in greater detail as the specification proceeds.

In order to facilitate ready comprehension of this invention for a proper appreciation of the salient features thereof, the invention is illustrated on the accompanying drawing forming part hereof, and in which:

Figure 1 is an elevation of our straight and slant bottom ruler as used upon the trouser leg of a customer to be fitted with a pair of trousers;

Figure 2 is another similar elevation of the ruler or gage on a larger scale in order to bring out certain details;

Figure 3 is a similar view to that of Figure 2 showing the ruler or gage from the other side than in Figure 2.

In the views, the same or like parts and features are indicated by the same numerals.

It is well known that in making garments, for example, men's trousers, considerable skill and experience are required to produce trousers that are capable of being well fitted. All too frequently, the fitting of trousers has been a haphazard matter, with the result that the trousers have been either too short or too long, because it is often troublesome to cut the trouser legs

2

just the right length for a given customer. Mainly, the reason for such difficulties being encountered is that there is no simple and easily applied standard for arriving at the correct length of trousers of any type. Rather often, the length is a matter of taste which differs among tailors as well as among their customers, and the net result is that such variation in trouser length may be noted that comparatively few are well fitted with such garments.

Upon considering this problem, it has occurred to us that a standard scale, ruler or gage should be available that may be applied directly to the leg of a pair of trousers and the length and bottom line directly gaged according to some uniform principle applicable to all trousers. As a result, we have succeeded in producing a special straight and slant bottom ruler or gage of the character already outlined, which we shall now proceed to describe in the following.

Hence, in the practice of our invention, and referring also again to the drawing, the ruler which is generally indicated at 10 primarily consists of a generally upright rule or scale 12 having a bottom cross piece 14 rigidly secured thereto. The rule or scale may be of wood, plastic, fibre or of any other material suitable for the purpose, the scale and cross piece being either glued, cemented, riveted or otherwise secured together, or even made unitary or in one piece, depending on the material used. Such methods and means of securing the two parts together or making them integral will readily occur to those skilled in the art and need not be elaborated on here.

In any event, it should be noted that the cross piece 14 is disposed at two different small angles with respect to the scale or rule 12. In other words, the angle between the scale and cross piece at one side 16 is greater than 90°, but the other angle between the scale and cross piece on side 18 is less than 90°, the result being that there is what we term a normal slight slant on the part of the scale with respect to the cross piece. Hence, the scale or rule leans back slightly when the cross piece 14 is placed squarely down on the floor.

Scale member 12 has a series of inch marks 20 along the edge 18 which may be the side of the smaller angle, while the bottom edge 22 has a similar row of markings 24. However, at the center of the bottom edge is formed a V-shaped slot directly below the center of the lower end of scale 12, and in corresponding manner, the upper end of this scale has a central V-shaped slot, both

slots indicating the seam 26 on a trouser leg 28, the lower slot 30 and the upper slot 32 being placed directly upon the seam when the device is to be used. When the scale is thus placed and the cross piece is at the lower end of the trouser leg, 5 advantage is taken of a transverse slot 34 to mark the leg through this slot with chalk, and the device is then raised just enough to bring the lower edge 22 of the cross piece to the mark thus made while again placing the V-shaped slots or notches 10 on the seam, and the cross piece will give the proper line for the trouser cuff 36, for example, and for the length of the leg 28.

If desired, a line 38 may be applied upon either or both sides of the scale to connect notches 30 15 and 32, an intermediate slot or peg opening breaking the line approximately midway, as noted at 40. The line 38 may thus indicate a nearly straight bottom for the trousers, the rear of each leg being of course slightly higher than the front 20 to allow for the shoe 42 in any case in normal manner. Upper slot 44 indicates the upper end.

On the other hand, it is often desired by very 25 stylish parties to have a greater slant to the bottom of the trousers, and for this case, a different feature is included as part of the scale and device as a whole. Beginning at the lower notch 30, a second line 46 is applied upon each side of the scale at a far more pronounced slant than that of the scale itself or its center line 33, but inclined in the same direction as the latter. At the upper portion of this line, it approaches edge 18, and if no special feature were added, the line 30 would terminate at the upper end 48 of the scale in abrupt manner and be almost unnoticeable. If 35 a notch similar to 32 were formed at the upper end of line 46, confusion might readily result, so that the wrong inclination would sometimes be selected, with dissatisfaction resulting.

In order to make the greater slant obvious and 40 distinctive, a slant index portion 50 is cut from the upper portion of scale edge 18 in line with slant line 46 when a pencil or narrow chalk is 45 drawn along this index portion. There is thus no possibility of confusing the regular so-called straight bottom condition of the device when the notches 30 and 32 are alined with seam 26, and the different and relatively great slant resulting when the lower notch 30 and the slant index 50 are both placed on the seam. Both slants are 50 not only different, but the indications for them are also so different that the difference is immediately evident without close inspection, and the particular slant desired is instantly available to be used.

As one side of the device is an exact duplicate of the other side in reverse, it serves equally well for both legs of a pair of trousers with the same results for both. It is obvious that we may use the present ruler or gage in more ways than as 60 explained above, but it is especially useful as a very effective standard for forming and cutting the legs of trousers to proper length at the correct angle so that a perfect fit uniformly results in all cases and is arrived at in a minimum of 65 time.

Manifestly, variations may be resorted to, and parts and features may be modified or used without others within the scope of the appended claims.

Having now fully described our invention, we claim:

1. A straight and slant bottom ruler or gage, including a generally upright scale having regular markings along one edge thereof, a cross piece secured at the intermediate portion thereof to the lower end of the scale in an angular relation thereto so that the cross piece is disposed at an angle of less than 90° with one side edge of the scale and at an angle of more than 90° with the other side edge of said scale, the cross piece having an intermediate slot disposed transversely of the scale, the lower edge of said cross piece having a V-shaped notch in line with said scale and the upper end of the latter having a corresponding V-shaped notch in the center thereof, said notches being adapted to be placed upon the seam of a trouser leg and in such position defining by the cross piece a normal slightly slanted bottom for said leg, and a slant index upon the upper portion of the scale with a line interconnecting said slant index and the V-shaped notch in the bottom edge of said cross piece to indicate a greater slant than that of the upper V-shaped notch when taken with the notch in said cross piece, the slant index including a cut out portion along a part of the edge upon one side of the scale at the upper end thereof, the cut out portion being alined with the line extending down to the V-shaped notch in the bottom edge of the cross piece for scribing a line with chalk in line with said line.

2. A straight and slant bottom ruler according to claim 1, wherein the V-shaped notches are interconnected by a separate line disposed at a small angle to the line connecting the slant index at the top with the V-shaped notch in the cross piece.

3. A straight and slant bottom ruler according to claim 2, wherein a transverse slot is disposed in peg position in the intermediate portion of the scale, and a second upper slot in the upper end of the scale to mark the length of a trouser leg.
